UNITED STATES PATENT OFFICE.

LUTHER L. KNOX, OF AVALON, PENNSYLVANIA, ASSIGNOR OF ONE-THIRD TO
MONTGOMERY MURRAY AND ONE-THIRD TO JOHN S. CRAIG.

METHOD OF MAKING HOLLOW SHEET-METAL STRUCTURES.

1,187,461.

Specification of Letters Patent. Patented June 13, 1916.

Application filed November 12, 1915. Serial No. 61,092.

To all whom it may concern:

Be it known that I, LUTHER L. KNOX, a citizen of the United States, residing at Avalon, in the county of Allegheny and State of Pennsylvania, have invented a new and useful Method of Making Hollow Sheet-Metal Structures, of which the following is a full, clear, and exact description, reference being had to the accompanying drawings, forming part of this specification, in which—

Figures 1, 2, 3, 4 and 5 are sectional views largely diagrammatic showing different steps in the manufacture of a twyer; and Fig. 6 is a sectional view of the finished twyer.

My invention has relation to the manufacture of hollow sheet metal structures, such as twyers; and is designed to provide a simple and efficient method by which such a structure may be formed from a single piece of sheet metal.

The nature of my invention will be best understood by reference to the accompanying drawings, in which I have illustrated my preferred form of twyer, together with the method of manufacturing the same.

In accordance with my invention, I provide a suitable sheet metal blank 2, of plate form, such as shown in section in Fig. 1, and by a series of drawing and shaping operations form therefrom a cylindrical body 3, closed at one end and open at the other. The successive shaping operations are of a nature to reduce the diameter of the cylindrical body while increasing its length, as indicated in Figs. 2 and 3. When the body has been thus formed to the required length and diameter, it is placed over a suitable former or anvil 4, in inverted position, and by means of a plunger, the closed bottom portion of the body is forced downwardly within the body in the manner illustrated in Fig. 4. The inner portion 5, which is thus forced downwardly within the anvil or former is made somewhat longer than the outer body portion 6. The structure as thus formed is then removed from the anvil or former and the closed end 7 of the portion 5 is cut out. The mouth part of the portion 6 is then expanded, as indicated at 8 in Fig. 5, and the portion 6 is also flared outwardly, as shown in said figure. The inner portion 5 is also similarly flared. The projecting portion 5^a of the portion 5 is then

bent downwardly and outwardly to close the space between the inner and outer walls of the structure, and the free edges thereof are welded to the upper edge of the portion 8. The portion 5^a is also perforated and suitable sleeves or bosses 9 and 10 are welded or otherwise secured in these perforations, to provide for water-circulating connection. The boss 9 may have secured therein a discharge pipe 11, which extends to a point 65 near the inner end of the structure.

My invention provides a sheet metal twyer whose body is formed from a single piece of metal and in which the only seam is the welded joint between the outer edge 70 of the portion 5^a and the portion 8. The method of manufacture described is a simple and comparatively inexpensive one and capable of being readily carried out on a commercial scale.

It will be apparent that various changes can be made in the precise form and shape of the finished article, as well as in the method of manufacture thereof, without departing from the spirit and scope of my 80 invention as defined in the appended claims.

I claim:

1. The herein described method of making hollow double wall sheet metal structures, which consists in shaping a sheet metal blank into an approximately cylindrical body closed at one end, then forcing a portion of said body from its closed end inwardly within the body, and expanding the inner and outer walls of the structure to frusto-conical form, substantially as described.

2. The herein described method of making hollow double wall sheet metal structures, which consists in shaping a sheet metal blank into an approximately cylindrical body closed at one end, then forcing a portion of said body from its closed end inwardly within and through the body in the reverse direction, and bending and stretching a portion of the said closed end portion over and outwardly to form a closure for the open end of the structure, substantially as described.

3. The herein described method of making hollow twyer structures, which consists in shaping a sheet metal blank into an approximately cylindrical body closed at one end and open at the other end, then forcing a portion of the body from the closed end 105 110 115

thereof inwardly within the body, and then utilizing a part of such portion to form a closure for the structure, substantially as described.

- 5 4. The herein described method of forming hollow twyer structures, which consists in providing a cylindrical sheet metal body closed at one end and open at the other end, then forcing a portion of such body from the closed end thereof inwardly within the body to form a double wall structure, and utilizing a part of said portion to form a closure between the inner and outer walls of the structure at the open end thereof, substantially as described.
- 10 15 5. The herein described method of form-

ing twyer structures, which consists in providing a cylindrical sheet metal structure closed at one end and open at the other end, forcing a portion of said structure inwardly within the body of the structure to thereby form an inner wall thereof, then shaping the inner and outer walls to the desired form, and finally utilizing a projecting portion of the inner wall to form a closure between the two walls, substantially as described.

In testimony whereof, I have hereunto set my hand.

LUTHER L. KNOX.
